UNITED STATES PATENT OFFICE

MAX ABEL, OF BRONX, NEW YORK, ASSIGNOR TO FRANKART, INC., OF NEW YORK, N. Y.,
A CORPORATION OF NEW YORK

DESIGN FOR AN ASH TRAY OR SIMILAR ARTICLE

Application filed September 3, 1931. Serial No. 41,008. Term of patent 3½ years.

To all whom it may concern:

Be it known that MAX ABEL, a citizen of Germany and resident of Bronx, in the county of Bronx and State of New York, has invented a new, original, and ornamental Design for Ash Tray or Similar Article, of which the following is a specification, reference being had to the accompanying drawing forming part thereof, in which,

The figure is a perspective view of an ash tray embodying my new design.

I claim:

The ornamental design for an ash tray or similar article, substantially as shown.

Dated, August 28th, 1931.

MAX ABEL.
